UNITED STATES PATENT OFFICE.

PHILIP S. MEDART, OF ST. LOUIS, MISSOURI, ASSIGNOR TO FRED MEDART MANUFACTURING COMPANY, OF ST. LOUIS, MISSOURI, A CORPORATION OF MISSOURI.

PLAYGROUND-SWING.

1,345,385.

Specification of Letters Patent.

Patented July 6, 1920.

Application filed January 17, 1920. Serial No. 352,064.

To all whom it may concern:

Be it known that I, PHILIP S. MEDART, a citizen of the United States of America, and a resident of the city of St. Louis, 5 State of Missouri, have invented certain new and useful Improvements in Playground-Swings, of which the following is a specification.

This invention relates to that class of 10 playground or pleasure swings in which the seat member is held in a suspended condition by a pair of pliable side connections, and has for its objects:—

To provide a simple and durable structural formation and association of parts, 15 wherein the seat member is connected to pliable suspension members of the swing in a durable and substantial manner with an elimination of the ordinary rapid fretting and wear of parts in actual use.

20 In the accompanying drawing:—

Figure 1, is a front elevation of a swing embodying the present improvements.

Fig. 2, is a side elevation of the same.

25 Fig. 3, is an enlarged detail section of a hand hold portion of the swing suspension member.

Like reference numerals indicate like parts in the different views.

30 Referring to the drawing, 1 designates the seat member preferably of the usual flat board form, to the respective ends of which are attached angle bracket members, each of which is formed with horizontal flange 35 or web 2 for attachment to the underside of the seat member 1, and with a vertical flange or web 3 of a triangular shape and having at its upper end out-turned flanges or ears 4 formed with alined orifices for the 40 reception of a pivot pin or rivet of the rocking head or clevis now to be described.

5 designates rocking heads or clevises individual to the aforesaid angle bracket members, with each clevis 5 pivoted between the flanges or ears 4 by a pivot pin or rivet 6. At their upper ends the clevises 5 are provided with alined pivot orifices arranged in right-angle relation to the aforesaid pivot pins 6 and adapted to receive 50 pivot pins or rivets 7 for connection to

the lower ends of the suspension members of the swing.

8 designates the pair of suspension members of the swing, each of which in the preferred form of the present invention 55 shown in the drawing comprises an upper chain portion of member 8' carrying at its upper end an attaching hook 9, an intermediate rod metal portion or member 8'' connected to the lower end of the chain portion 8' by a link 10, and a lower rod metal portion or member 8'' pivotally connected to the lower end of the intermediate portion 8'' and to a head or clevis 5 by a pivot pin 60 or rivet 6 aforesaid. In the preferred detail construction shown, the upper and lower ends of the intermediate portion or member 8'' are screw-threaded for engagement with heads 11 which in turn are formed for pivotal connection to the upper 65 chain portion 8' and to the lower rod portion 8'' as shown more particularly in Fig. 3.

12 designate hand holds or grips carried by the aforesaid intermediate portions 75 or members 8'' of the suspension members of the swing. In the present construction the hand holds or grips 12 consist of sections of rubber or like tubing slipped over the intermediate members 8'' and held in 80 place by cup shape caps 13, as illustrated in Fig. 3. Such construction is shown and substantially claimed in my prior application, Serial No. 338,424, filed November 17, 1919.

85 Having thus fully described my said invention what I claim as new and desire to secure by Letters Patent, is:—

1. In a swing, the combination of a seat, a pair of flexible suspension members, and 90 attachments between the seat and suspension members, each attachment comprising an angle-bracket having a horizontal attaching flange, a vertical flange formed with a pair of out-turned orificed ears, and a 95 clevis pivotally attached to said ears and to the lower end of a suspension member, the respective pivot axes having a right-angle relation.

2. In a swing, the combination of a seat, 100

a pair of flexible suspension members, and attachments between the seat and suspension members, each attachment comprising an angle-bracket having a horizontal attaching flange, a vertical flange of a triangular shape and formed with a pair of out-turned orificed ears, and a clevis piv-

otally attached to said ears and to the lower end of a suspension member, the respective pivot axes having a right-angle relation.

Signed at St. Louis, Missouri, this 12th day of January 1920.

PHILIP S. MEDART.
